CLAIM

The ornamental design for a network gateway, as shown and described.

DESCRIPTION

FIG. 1 is a front elevational view of a network gateway showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, top and right-side perspective view thereof;

FIG. 8 is a rear, top and left-side perspective view thereof;

FIG. 9 is a rear, top and right-side perspective view of the network gateway with a single mounting bracket mounted on the rear thereof;

FIG. 10 is rear, top and right-side perspective view of the network gateway with the single mounting bracket mounted on the right thereof;

FIG. 11 is a rear, top and right-side perspective view of the network gateway with dual mounting brackets mounted on the rear thereof; and,

FIG. 12 is a rear, top and right-side perspective view of the network gateway with dual mounting brackets mounted on the right thereof.

The broken lines shown in the drawing represent subject matter and form no part of the claimed design.
